Primary Examiner — Catherine Tuttle(74) *Attorney, Agent, or Firm* — Miller, Matthias & Hull LLP**CLAIM**

The ornamental design for a fluid dispensing device, as shown and described.

DESCRIPTION

FIG. 1 is a perspective view showing our new design for the fluid dispensing device;

FIG. 2 is a front view thereof;

FIG. 3 is a rear view thereof;

FIG. 4 is a right side view thereof, the left side view being a mirror image of the right side view;

FIG. 5 is a top view thereof; and,

FIG. 6 is a bottom view thereof.
